[57] CLAIM

The ornamental design for a foal gate, as shown and
described.

DESCRIPTION

FIG. 1 is a perspective view of a foal gate showing our new
design;

FIG. 2 is a front view thereof;

FIG. 3 is a top view thereof;

FIG. 4 is a bottom view thereof;

FIG. 5 is a rear view thereof;

FIG. 6 is a right side view thereof as viewed in FIG. 2; and,

FIG. 7 is a left side thereof as viewed in FIG. 2.

The foal gate is broken in the center to indicate indeterminate
length.
